UNITED STATES PATENT OFFICE.

HENRY C. GEORGE, OF PHILADELPHIA, PENNSYLVANIA.

WINDOW.

Application filed June 15, 1922. Serial No. 568,387.

To all whom it may concern:

Be it known that I, HENRY C. GEORGE, a citizen of the United States, residing at Philadelphia, county of Philadelphia, and State of Pennsylvania, have invented a new and useful Improvement in Windows, of which the following is a full, clear, and exact description, reference being had to the accompanying drawings, which form a part of this specification.

My invention relates to swinging or pivoted windows.

The object of my invention is to provide novel means for hanging or pivoting window sash, so constructed as to permit the window to be readily turned for opening and closing and at the same time so constructed as to eliminate any tendency for the relatively moving parts of the pivoting means to come apart from repeated relative rotation. Further, to provide means so constructed as to be readily assembled and disassembled and at the same time accurate and efficient in operation.

Heretofore in windows of the swinging or pivoted sash type, such, for example, as windows wherein the sash is horizontally pivoted to a shoe, difficulty is commonly experienced from the fact that since the fixed and turnable members of the pivots are usually secured together by means of a bolt and nut, with repeated swinging of the window on its pivots in opening and closing, the nut becomes loose and as a result the sash becomes loose and works inaccurately.

By virtue of my invention, a pivot is provided the movable member of which is so secured to the fixed member as to eliminate any tendency toward separation of the members, irrespective of the frequency with which the window is swung on its pivots.

Further, by virtue of my invention, the window when closed will be tight and draughts will be eliminated.

Having now indicated in a general way the nature, purposes and advantages of my invention, I will now proceed to a detailed description of a preferred embodiment thereof, with reference to the accompanying drawings, in which—

Fig. 1 is a face view of a shoe and sash pivoted thereto, constructed in accordance with my invention.

Fig. 2 is an elevation of a shoe and a portion of the sash pivoted thereto.

Fig. 3 is an inner face view of a shoe.

Fig. 4 is a cross-sectional view through the shoe and sash, with the window in closed position.

Fig. 5 is a face view of a portion of the sash and the pivotal member thereon.

Fig. 6 is a cross-sectional view showing my improved pivoting means.

Fig. 7 is an enlarged face view of the pivoting member on the shoe.

In these drawings in which I have merely shown one shoe, a portion of a sash and the connections between the sash and the shoe, the reference character *a* designates the shoe, *b* the sash and *c* the glass in the sash.

The adjacent faces of the shoe *a* and sash *b* are recessed for the reception of the body portions of the socket pivot members *x* and *y*, the pivot member *x* being secured to the shoe *a*, while the member *y* is secured to the sash.

The shoe is provided with a through opening and is counter-bored from both sides concentric with said opening. Seated in the deepest counter-bore or the counter-bore in the inner side of the shoe, is a cylindrical boss or bearing member on the pivotal member *x*. This boss is provided with cylindrical recess *z* and a flange having an opening *d* concentric with the recess *z*. The flange is also provided with a slot *e* communicating with opening *d*. The pivot member *y* is provided with a hollow trunnion *f* which is seated on recess *z* which forms a bearing therefor.

The inner end of the trunnion *f* is also provided with an internal annular flange surrounding an opening *g* of the same diameter as opening *d*. The flange on trunnion *f* is provided with a key seat *h* communicating with opening *g*.

The pivot members *x* and *y* are secured to each other by means of a pin *i* and screw *l*. The pin *i* is tapped for the reception of screw *l*, and is provided with a head *j* which engages the inner face of the flange of trunnion *f*, and is also provided with a short key *k* movable through key seat *h*. The key *k* extends from the one end of the pin *i* to a point adjacent to the head *j*, there being a space between the end of the key and the head *j* in which the flange of member *f* is adapted to rotate.

Secured to the shoe *a* and sash *b* are strips *m*, *m*, each having an inner overhung flange

o and an outer bead n. The flanges o on the shoe a and sash b are arranged to be seated as shown in Fig. 4 to form throughout the length of the strips a weather tight joint between the shoe and sash. If desired, a packing, such as felt, may be positioned in the space p between the flanges o of the strips m.

In assembling, the pin i is inserted through opening g in member y, the key k being passed entirely through key way h. The pin i is then rotated a substantial distance to move the key k out of register with the key way h. The members x and y may then be fastened to the shoes a and sash b, respectively, the shoes with their members x positioned on members y, and when positioning those members, the keys k on pins i are inserted in the key seats e in the member x. The screws l are then positioned to jam the ends of the pins i against the bottoms of the counter-bores in the sides of the shoes a adjacent the sides of the sash, and when the pins i are so secured the members x and y will be held against substantial movement along the axis of the swinging sash. The connected shoes and sash can then readily be positioned in the frame.

Having now fully described my invention, what I claim and desire to protect by Letters Patent is:

1. In a window structure comprising a sash and a shoe associated therewith, means for pivotally connecting said shoe and sash comprising a pair of pivot members, one

mounted on the shoe and the other on the sash, the pivot member connected to the shoe having a flanged hollow boss seated in a recess in the shoe, the pivot member on the sash having a flanged hollow trunnion journalled in the hollow boss of the pivot member on the shoe, a fastening member for securing the pivot members to each other against movement along the axis of the members and extending through the flanges of the hollow trunnion and the hollow boss, and means for securing the fastening member to the shoe.

2. In a window structure comprising a sash and a shoe associated therewith, means for pivotally connecting said shoe and sash comprising a pair of pivot members one connected on the shoe and the other on the sash, the pivot member on the shoe having an internally flanged hollow boss, there being a key-seat in said flange, the pivot member on the sash having an internally flanged hollow boss seated in the boss in the pivot member on the shoe and in which it is arranged to rotate, a pin extending through the flanges on the bosses having a head within the inner boss arranged to be engaged by the flange on the inner boss, a key on said pin seated in the key seat, and a screw for securing the pin to the shoe.

In testimony of which invention, I have hereunto set my hand at Philadelphia, Pa., on this 12th day of June, 1922.

HENRY C. GEORGE.
